UNITED STATES PATENT OFFICE.

ARTHUR SIDWELL, OF WALTHAM, MASSACHUSETTS, ASSIGNOR TO WALTER MEASURE, OF NEEDHAM, MASSACHUSETTS.

DESIGN FOR A TREAD-PIECE FOR BICYCLE-PEDALS.

SPECIFICATION forming part of Design No. 25,424, dated April 21, 1896.

Application filed July 29, 1896. Serial No. 557,508. Term of patent 31 years.

To all whom it may concern:

Be it known that I, ARTHUR SIDWELL, of Waltham, county of Middlesex, State of Massachusetts, have invented and produced a new and original Design for Tread-Pieces for Bicycle-Pedals, of which the following description, in connection with the accompanying drawings, is a specification, like letters on the drawings representing like parts.

10. The design is embodied in a tread-piece for bicycle-pedals of the kind known as a "rat-trap" pedal, having parallel flat-metal tread-bars serrated or roughened at their edges on which the foot of the rider bears.

15. Figure 1 is a perspective view of a bicycle-pedal, showing my design; and Fig. 2, a side elevation thereof.

The leading feature of my design consists in the tread-piece $a a^2 a^3$, of a general U shape, 20 the side portions or tread-bars $a a^2$ thereof being parallel with one another and the end portion a^3 connecting the ends of said portions $a a^2$. One end of the side portion a is

provided with a curved horn a^4 , projecting beyond the line of one edge thereof, and the other side portion a^2 is provided with a similar horn a^5 , projecting beyond the opposite edge of said portion a^2 . The end portion a^3 , of arch-form, has the central substantially circular opening a^6 and the horns or projections a^7 on opposite sides thereof. It has also the openings a^8 and marginal strips a^9 . The tread-bars have the diamond or lozenge shaped openings b and triangular openings c , the several openings in the tread-piece giving it a skeleton or open-work effect.

What I claim is—

The design for a tread-piece for bicycle-pedals, substantially as shown and described.

In testimony whereof I have signed my name to this specification in the presence of two subscribing witnesses.

ARTHUR SIDWELL.
